UNITED STATES PATENT OFFICE.

HENRY PEARSON, OF BRIGHTWOOD, MASSACHUSETTS, ASSIGNOR, BY MESNE ASSIGNMENTS, TO THE J. G. BRILL COMPANY, OF PHILADELPHIA, PENNSYLVANIA, A CORPORATION OF PENNSYLVANIA.

UNLOADING APPARATUS.

1,381,495.

Specification of Letters Patent. Patented June 14, 1921.

Application filed June 1, 1918. Serial No. 237,683.

To all whom it may concern:

Be it known that I, HENRY PEARSON, a citizen of the United States, and a resident of Brightwood, county of Hampden, and 5 State of Massachusetts, have invented an Improvement in Unloading Apparatus, of which the following description, in connection with the accompanying drawings, is a specification, like characters on the drawings 10 representing like parts.

This invention relates to unloading apparatus, and is more especially, though not exclusively, concerned with a dumping body for vehicles of the class in which dumping 15 movement of the body is utilized to unlock the gate or closure of the receptacle, thereby to permit the load to be released from the discharge opening.

My invention will be best understood by 20 reference to the following description, when taken in connection with the accompanying drawings of one specific embodiment thereof, while its scope will be more particularly pointed out in the appended claims.

25 In the drawings:

Figure 1 is a side elevation of a motor truck equipped with a dumping body embodying my invention, showing in full lines the body in the position which it normally 30 occupies, and in dotted lines an illustrative dumping position;

Fig. 2 is a rear elevation of a portion of the same on an enlarged scale;

Fig. 3 is a side elevation at the same scale 35 as Fig. 2, showing in its normal position the locking and unlocking mechanism, and portions of the body and its supporting frame; and

Fig. 4 is a view similar to Fig. 3 and at 40 the same scale, but partly in vertical section, showing the same parts in dumping position.

Referring to the drawings, and to the embodiment of my invention which is illustrated therein for purposes of exemplification, I have shown a common form of motor truck having a chassis frame 5, on which is supported a dumping body 6 comprising a receptacle 7 having a discharge opening 8, 45 which is normally closed by a gate 9, the latter being preferably suspended from pivots 10, whereby it is adapted to gravitate toward an open position when the body 50 is in a dumping position, and to gravitate

toward its closed position when the body is 55 restored to its normal position, as will be evident from an inspection of Fig. 1.

The body may be mounted in any appropriate manner for tilting movement, whereby its load may be dumped, but in the present example, I have shown the same fulcrumed on pivots 11 on brackets 12, the latter being secured to the chassis frame 5. My present invention is not concerned with the mechanism for tilting the body to dump 65 the load, but I have shown an illustrative dumping mechanism of common form, comprising a vertically extensible column 13, on which is supported a winding drum or drums 14 for a cable or cables 15, connected 70 to a frame 16, the latter being rigidly secured to the receptacle 7.

As a means for automatically locking and unlocking the gate 9, without requiring manual operation by the truck driver, I 75 have shown mechanism which may be and preferably is in duplicate, though constructed in right- and left-hand arrangement, as best shown in Fig. 2. A description of one of these mechanisms will suffice 80 for both.

Each of these mechanisms may comprise a suitable latch 17, engaging an appropriate abutment 18, the latter in the present example being in the form of a bar, preferably 85 an angle iron, which is secured to and extends laterally beyond the gate 9, as best shown in Fig. 2. Preferably, the arrangement of the latch 17 is such that it tends to gravitate toward its locking position, and 90 to that end, in the present example, it is arranged in a generally horizontal position, and is mounted on a pivot 19 to swing about a horizontal axis. This pivot may be connected by appropriate means to the supporting frame 5, so that tilting movement of the body 6 will be accompanied by fore-and-aft movement of said pivot and latch. To this end, in the present example the pivot 19 is carried by an arm 20, the latter being secured to a rock-shaft 21 mounted in suitable bearings 22 and 23 on the under side of the receptacle 7, as best shown in Fig. 2. Also secured to this shaft is a second arm 24, best shown in Figs. 3 and 4, which is 95 suitably connected to the frame 5, as by a link, or preferably a pair of links, 25, best shown in Fig. 2.

When, during the tilting movement of the body 6 about the axis of the pivots 11, the pivots 21 describe an arc struck from said axis as indicated in Figs. 3 and 4, the described connections impart a generally horizontal movement to the latch 17. This movement is utilized to cause the latch to move in another direction to lock or unlock the gate, as the case may be. To this end, I have herein provided coöperating means carried by the receptacle 7 and latch 17, such means comprising inclined surfaces 26 and 27, best shown in Fig. 4. When the latch 17 is moved in a rearward direction, its inclined surface 27 rides up the stationary inclined surface 26, and said latch is lifted while being moved rearwardly, thereby releasing the gate 9, and allowing the latter to open as indicated by dotted lines in Fig. 1. When, on the other hand, during the restoration of the body to its normal position, the latch 17 moves in a forward direction, the inclined surfaces 26 and 27 allow the latch to gravitate toward its normal position. During the downward and forward movement of the latch, the latter will engage the abutment 18 of the gate 9, and move said gate toward its closed position.

If the gate is unobstructed, the latch will carry the same to its fully closed position, from which it will then be locked. If, however, the gate meets with some obstruction, such for example as material which has clogged the same, I have provided yielding means to permit the dumping receptacle to move toward its normal position, without injury to the mechanism. To these ends, I have provided a suitable spring 28, appropriately connected to the links 25 in such a manner as to permit a yielding action to take place between the latter and the frame 5. This spring may be otherwise appropriately arranged, but in the present example, it encircles a rod 29, which is provided with an ear 30 pivotally connected to said links. The lower end of the spring bears against an abutment 31 carried by the rod 29, while the upper end bears against an abutment 32, which in turn bears against a fixed abutment 33 in the form of a bracket secured to the bracket 12. This spring may be sufficiently heavy unyieldingly to resist any ordinary pull tending to compress the same, such for example as that which is exerted by the load against the gate when the body is in its normal position. Under such conditions, any tendency to open the gate is resisted by the spring. When, however, during the closing and locking of the gate under the influence of the latch, an obstruction tends to prevent further closing movement of the gate, the spring is adapted to yield, thus allowing the body to return to its normal position without breakage of the parts.

While I have herein shown and described one specific form or embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment may be made, without departing from the principles thereof.

Having thus described my invention, what I claim and desire by Letters Patent to secure is:

1. In a load-discharging apparatus, the combination of a dumping receptacle having a discharge opening, a gate normally closing said opening, and means including a normally unyielding spring and consequent upon movement of said receptacle to close said gate.

2. In a load-discharging apparatus, the combination of a dumping receptacle having a discharge opening, a gate normally closing said opening, and means including a normally substantially unyielding spring to utilize movement of said receptacle toward its normal position to close said gate.

3. In a load-discharging apparatus, the combination of a dumping receptacle having a discharge opening, a gate normally closing said opening, and means to utilize movement of said receptacle toward its normal position to close said gate, said means including a latch, and a spring constituting a normally unyielding latch-actuating medium arranged to yield if and when said gate meets an obstruction during its closing movement.

4. In a load-discharging apparatus, the combination of a dumping receptacle having a discharge opening, a gate normally closing said opening and carrying an abutment, a latch normally engaging said abutment and yieldingly locking said gate, means consequent upon tilting movement of said receptacle to move said latch in a generally horizontal direction, and coöperating inclined surfaces carried by said receptacle and said latch to cause the latter to move in another direction to lock and unlock said gate.

5. In a load-discharging apparatus, the combination of a dumping receptacle having a discharge opening, a gate normally closing said opening and carrying an abutment, a latch normally engaging said abutment and locking said gate, means consequent upon tilting movement of said receptacle to move said latch in a generally horizontal direction, and means including a fixed support and a spring interposed between said support and said latch to permit the latter to move said gate with yielding pressure toward its closed position, and coöperating

means carried by said receptacle and said latch to cause the latter to move in another direction to lock and unlock said gate.

6. In a load-discharging apparatus, the combination of a dumping receptacle having a discharge opening, a gate normally closing said opening, a latch normally locking said gate, a support on which said receptacle is mounted to tilt, and latch-operating means connecting said latch to said support, and including resilient means tending to move said gate toward a closed position when restrained by said latch.

7. In a load-discharging apparatus, the combination of a dumping receptacle having a discharge opening, a gate normally closing said opening, a latch normally locking said gate, a support on which said receptacle is mounted to tilt, and latch-operating means connecting said latch to said support, said latch-operating means including normally unyielding resilient means consequent upon movement of said receptacle toward its normal position to move said gate toward its closed position.

8. In a load-discharging apparatus, the combination of a dumping receptacle having a discharge opening, a gate normally closing said opening, a latch normally locking said gate, a support on which said receptacle is mounted to tilt, and latch-operating means connecting said latch to said support, said latch-operating means including means consequent upon movement of said receptacle toward its normal position to move said gate toward its closed position, and resilient

means to permit said receptacle to continue to move toward its normal position when said gate is obstructed and said latch is tending to move the same toward its closed position.

9. In a load-discharging apparatus, the combination of a dumping receptacle having a discharge opening, a gate normally closing said opening, a latch normally locking said gate, a support on which said receptacle is mounted to tilt, and latch-operating means connecting said latch to said support, said latch-operating means including means consequent upon discharging movement of receptacle to unlock said gate and consequent upon movement of said receptacle toward its normal position to move said gate toward its closed position, and yielding means to permit said receptacle to continue to move toward its normal position when said gate is obstructed and said latch is tending to move the same toward its closed position.

10. In a load-discharging apparatus, the combination of a pivoted dumping receptacle having a discharge opening, a gate normally closing said opening, and gate locking and unlocking means comprising a latch which normally locks said gate, and means consequent upon pivotal movement of said receptacle about its pivotal axis to positively operate said latch in one direction to unlock said gate and yieldingly to operate said latch in another direction to lock said gate.

In testimony whereof, I have signed my name to this specification.

HENRY PEARSON.
